(57) **CLAIM**

The ornamental design for a fishing line reel spooler, substantially as shown and described.

DESCRIPTION

FIG. 1 is a perspective view of a fishing line reel spooler showing my new design. The fishing rod is shown in broken lines for illustrative purposes only and forms no part of the claimed design;

FIG. 2 is an exploded front elevational view thereof;

FIG. 3 is a elevational cross-sectional view taken on the line 3—3 in FIG. 5 thereof;

FIG. 4 is a left side elevational view thereof;

FIG. 5 is a rear elevational view thereof;

FIG. 6 is a top plan view thereof;

FIG. 7 is a bottom plan view thereof; and,

FIG. 8 is a right side elevational view thereof.
